ATTORNEYS

UNITED STATES PATENT OFFICE.

JOHN G. SNYDER, OF NEW YORK, N. Y.

TIE AND FASTENER.

Application filed June 20, 1924. Serial No. 721,251.

To all whom it may concern:

Be it known that I, JOHN G. SNYDER, a citizen of the United States, and a resident of the city of New York, borough of Manhattan, in the county and State of New York, have invented a new and Improved Tie and Fastener, of which the following is a full, clear, and exact description.

This invention relates to railway ties and fasteners and has for an object to provide an improved simplified construction wherein the tie is provided with reinforcing means extending its full length.

Another object of the invention is to provide a metallic tie for railways wherein H-shaped fastener plates are utilized which act in the double capacity of additional supporting means for rails and as means for receiving clips for locking the rails in place.

20 A still further object is to provide a tie and fastener in which the structure is such that a single fastening clip may be used adjacent each end of the tie or a plurality.

An additional object is to provide a construction which is in part a continuation of my prior application, Serial No. 461,208.

In the accompanying drawings—

Figure 1 is a perspective view of the tie and fastener structures embodying the invention, the tie being broken away at one end and one set of fastener clips being omitted for better illustrating the construction.

Figure 2 is an enlarged transverse sectional view through Figure 1, approximately on line 2—2.

Figure 3 is an enlarged detail perspective view of one of the clips shown in Figure 1.

Figure 4 is a perspective view similar to one end of the structure shown in Figure 1 but disclosing a modified form of plate.

Figure 5 is a view similar to Figure 4 but showing a modified form of plate wherein a number of notches are provided to permit adjustment of the rail gage.

Figure 6 is an inverted perspective view of a clip adapted to be used in connection with the structure shown in Figure 5.

Referring to the accompanying drawings by numerals, 1 indicates the body of the tie which may be made of any desired length

and project any desired distance beyond the rails positioned on the plates 2 and 3, which plates are of identical construction and are held in place by any suitable means, as for instance, rivets, though bolts, welding or other means might be used. The body 1 is provided with a longitudinal groove 4 positioned centrally of the top and extending for the full length of the tie. This groove preferably is open at each end as clearly illustrated in Figure 1 whereby dirt or foreign matter may be readily removed by a pick or other instrument and also whereby a bolt head may be readily inserted.

As indicated at the right in Figure 1, the plates 2 and 3 are H-shaped whereby a central section 5 is provided on which the base of the rail rests. This provides additional support for the rail. It will also be noted that the plates 2 and 3 are provided with slots 6 and 7 whereby overhanging portions 8 and 9 are produced, said overhanging portions forming shoulders overhanging the groove 4, which groove is preferably formed by pressing downwardly some of the material of the tie and thereby producing what may be termed a reinforcing bead when viewed from the under surface. This groove structure, therefore, performs a double function, namely, a reinforcing function and also the function of providing walls against which the heads of the various bolts 10 may strike when the nuts of these bolts are tightened.

A notch 11 is provided on each side of each slot 6 and 7 whereby a depending holding member or flange 12 may fit therein when the respective clips 13 are mounted in position as shown at the left in Figure 1. It will be noted that these clips are each provided with an aperture 14 for receiving the bolt 10, a shoulder 15 for engaging the edge of the base of the rail and an overhanging section 16 for engaging the upper surface of the base of the rail. By this construction and arrangement, it will be observed that the clip overlaps or extends beyond the respective slots 6 and 7 an appreciable distance which produces an apron effect to cover the slots at this point.

When it is desired to fasten a rail in po-

sition, as for instance, on plate 3, the rail is positioned centrally of the plate so as to cover section 5 and then two clips 13 are placed in position as shown at the left in 5 Figure 1. Before the clips are placed in position, the heads of two bolts are placed in the groove 4 adjacent opposite ends of the plate 3 and these bolts slid toward each other until they extend through the slots 6 and 7 at substantially the correct position.

10 The clips are then placed over these bolts so that the bolts will extend through the apertures 14 in the clips and the holding members 12 will fit into the respective 15 notches 11. The nuts are then applied and screwed down tight as shown at the left in Figure 1. As the nuts are screwed down tight, the side walls of the groove 4 will act to prevent the bolts from turning and, consequently, the heads of the bolts will be 20 pulled up tight against the overhanging shoulders 8 and 9 as illustrated particularly in Figure 2. The depending end 12 may be termed a single holding member or may 25 be termed holding members, as the opposite ends act independently in the respective notches 11.

In Figure 4, a modified construction of fastener plate 2' is disclosed wherein the 30 ends are closed by the respective sections 17 and 18 which are preferably integral with the remaining part of the plate. However, this plate is provided with the usual slots 6 and 7 but these slots merge into large openings 19 and 20 adapted to permit the passage of the head of the clamping bolts 10. The openings 19 and 20 in turn merge into the 35 respective notches 11'. When this form of fastener plate is to be used, which is a substantially H-shaped plate with closed ends 17 and 18, the plate is riveted or otherwise secured in place as shown in Figure 4 and a rail placed centrally thereon. The heads of two bolts are passed through the openings 19 and 20 and the bolts moved toward each 40 other until they project through the slots 6 and 7. Two clips 13 are then applied as above described and the nuts for the bolts are tightened in the usual manner.

45 In Figures 5 and 6 will be seen a modified construction wherein the H-shaped fastener plate 21 is riveted in place similar to the other forms of plate. This plate is provided with slots 6 and 7 extending to the ends of 50 the plate. However, instead of having merely one notch 11 on each side of each of the slots, there is provided a series of notches 11" on each side of each slot whereby the clip 13' may be used and the gage of the 55 rail taken up. Under some circumstances, the inner face of the ball of the rail wears away and it is desired to move the rails toward each other to take up this wear. By providing a series of notches, the distance 60 between the rails may be adjusted at any

time with ease by merely shifting the holding members 22 and 23 of the depending end flange 24 from one set of notches 11" to another set. Aside from this arrangement of notches, the fastener plate 21 is identical 70 with that shown in Figure 1. Also the clip 13' is identical with the clip 13 shown in Figure 3 except for the beveled holding members 22 and 23 formed to properly fit into the notches 11".

75 In constructing the tie body 1, the same may be made comparatively short for narrow gage work or may be made longer and larger in every respect for regular railway service. In forming the tie body, the same 80 is formed as an inverted trough preferably with closed ends. The edges may be rounded or more or less sharp as indicated in Figure 2 without departing from the spirit of the invention.

85 What I claim is:

1. A tie and fastener for railways, comprising a trough-shaped metallic tie body formed with a groove in the top extending from one end to the other, means acting 90 as a fastener plate formed with sections overlapping said groove for presenting spaced overhanging shoulders, a clip mounted on said plate for clamping a rail to the plate, and a bolt extending through 95 said clip, said bolt having its head positioned in said groove, said head being of such a size as to engage the side walls of the groove sufficiently to prevent turning thereof, said head interlocking with said overhanging shoulders when in clamping position.

100 2. In a tie and fastener for rails, a tie body provided with an H-shaped fastener plate, certain parts of said plate presenting shoulders, a clip, and a bolt having its head engaging said shoulders, said bolt acting on said clip for clamping the same to said clip.

105 3. In a tie and fastener for rails, a tie body, an H-shaped tie plate mounted on said tie body, and means interlocking with said tie plate for clamping a rail on the plate.

110 4. A tie and fastener for rails, comprising a trough-shaped tie body formed with a centrally positioned groove in the top, an H-shaped fastener plate mounted on top of said body and positioned so that one edge of each leg of the H will overlap the groove for presenting a shoulder overhanging the 115 groove, a clip for each of said plates, and a bolt for each clip for locking the same in place, said bolts being positioned with their heads in said groove and interlocking with said shoulders.

120 5. In a rail fastener, a fastener plate having grooves extending from opposite ends inwardly whereby an H-shaped structure is provided, said plate being also provided with a plurality of notches adjacent each 130

end merging into said grooves, and means co-acting with said plate for clamping a rail thereon, said means including a bolt extending through one of said slots and having its head engaging the under surface of the fastener plate.

6. A tie and rail fastener, comprising a tie body formed with a groove in the top extending for the full length of the tie

body, the material forming the groove presenting a reinforcing bead on the under surface of the tie body, means extending over said groove presenting overhanging shoulders extending longitudinally of the tie body, and means interlocking with said shoulders for clamping a rail to said tie body.

JOHN G. SNYDER.
